(57) CLAIM

The ornamental design for a beverage vending machine, as shown and described.

DESCRIPTION

FIG. 1 is a perspective view of a beverage vending machine showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line showing on FIGS. 1, 2, 4 and 6-7 is for illustrative purposes only and forms no part of the claimed design.

1 Claim, 7 Drawing Sheets
